WINDOW SAFETY GUARD

Nicholas F. Busillo, 1340 Woodland Road, Rydall, Pa.
Filed May 29, 1963, Ser. No. 284,193
1 Claim. (Cl. 29—71)

This invention relates to a window safety guard and, in particular, to a safety guard which is designed to be inserted and removed from an ordinary window frame as desired, while preventing access through the open window when in the inserted position.

It is the primary object of this invention to provide a window safety frame which can easily be inserted in an ordinary window frame wherein only a few locking parts are permanently installed, the safety guard having locking means which can quickly be engaged and released.

It is another object of this invention to provide a light weight window safety guard of inexpensive construction having locking apparatus which is so designed that a child on the inside of the window could not unfasten and remove the frame by himself.

These objects and other attendant advantages will become more apparent from the description herein and from the attached drawings, wherein:

FIG. 1 is a perspective view of an ordinary window having two sashes mounted for vertical movement, with one form of the safety guard of this invention shown in the installed condition;

FIG. 2 is a fragmentary perspective view of the window guard employing a modified locking apparatus;

FIG. 3 is a sectional view, partly in elevation, of the two sashes showing the safety guard in position before locking;

FIG. 4 is a sectional view, partly in elevation, taken along the lines and arrows IV—IV of FIG. 1, showing the inner sash in the lowered position;

FIG. 5 is a sectional view, partly in elevation, showing a modification of the locking means with the inner sash raised;

FIG. 6 is a sectional view taken along the lines and arrows VI—VI of FIG. 2 showing the inner sash lowered;

FIG. 7 is a sectional view taken along the lines and arrows VII—VII of FIG. 1 showing the two sashes locked together;

FIG. 8 is a sectional view taken along the lines and arrows VIII—VIII of FIG. 1;

FIG. 9 is a perspective view of a locking member; and

FIG. 10 is a perspective view of a locking member and a holding means forming a modification of the holding means shown in FIG. 9.

Referring, preliminarily, to FIG. 1 of the drawings, an ordinary window frame is generally designated by the numeral 10 and consists of two vertical side frame members 12 and 14, a top transverse member 16 and a sill 18 located at the bottom of the frame 10. Mounted within the window frame 10 are two sashes, an inner sash 20 and an outer sash 22, shown in broken lines. Both sashes, as is the ordinary practice, are mounted for vertical movement within the window frame 10. It should be understood, however, that the safety guard of this invention need be only slightly modified so as to accommodate sashes which are mounted for horizontal movement.

The preferred form of the window safety guard of this invention, shown in FIGS. 1 and 2, is generally designated by the numeral 30. This form consists of a frame 32 extending around the guard, the frame 32 being substantially the size of a single window sash so that it occupies completely the lower half of the window. Within frame 32 are permanently mounted a plurality of bars or cables 34 preferably of a strong metal, so that passage through the center of the frame is prevented. These

bars can be of any desired shape and form and can be attached to the frame 32 as desired. Two U-shaped channels 36 are permanently fixed to the vertical window frame members 12 and 14 at the bottom. These channels 36, each having a single open end 36a, are mounted inside the inner sash 20 so that when the safety guard 30 is not in place within these channels as shown in FIG. 1, the channels 36 do not in any way hinder movement of either sash or full utilization of the window. The channels are preferably formed from a metal such as aluminum or iron and can be secured to the window frame by any suitable means.

The safety guard frame 32 itself is of such thickness and width as to slide easily in the channels 36 but be firmly held therein so that the guard is inserted in the channels by dropping it in the open ends 36a.

The window safety guard locking means 40, as shown in FIG. 1, consists of a round metal bar having opposingly directed end portions 40a, 40b, shown in greater detail in FIG. 9. When the safety guard is in place, the end portion 40b is mounted within a circular channel or hole in the top edge of the guard frame while portion 40a is similarly mounted in the bottom edge of sash 20 as described hereinbelow.

25 A modification of the locking means is shown in FIG. 2 of the drawing. The locking bar 50, shown also in greater detail in FIG. 10, when in place, has a lower portion 50b mounted within a channel on top of guard frame 32 and a top portion 50a mounted in a catch 54.

30 FIG. 3 is a sectional view of the two sashes and shows bar 40 mounted within a circular channel or hole 38 formed in the top of guard frame 32. Both the inner sash 20 and the outer sash 22 are raised to the top of the window frame and above the safety guard so that bar 35 40 is positioned to slide within channel 21 in the bottom of the inner sash where that sash is lowered. In FIG. 4, the inner sash 20 has been lowered so that the upper portion 40a of the bolt 40 fits within the circular channel 21 made in the bottom of the sash 20. When bar 40 is fitted within both the safety guard and the inner sash, the safety guard cannot be moved vertically out of channel 36 until the sash 20 is raised so as to clear the upper bar portion 40a. Bar 40 can be pivotally mounted in guard frame 32 so that the bar remains in the plane of the safety guard while the guard is inserted in channel 36 after which the bar is pivoted to the position shown in FIGS. 3 and 4.

Referring now to FIGS. 5 and 6 wherein a modification of the locking means shown in FIGS. 3 and 4 is illustrated. The locking means of FIGS. 5 and 6 correspond to that shown in FIG. 2 and comprises a locking bar 50 having a lower portion 50b mounted within a circular channel 39 in the top of the guard frame. The upper portion 50a is located and remains in the same plane as the window guard substantially as shown. A catch 54, secured by a pair of screws 56, is mounted on the lower inner edge of the inner sash 20 in a position so as to receive the upper bar portion 50a when the latch 20 is moved downwardly as shown in FIG. 6. After the safety guard has been placed within channels 36 the inner sash is lowered, as shown in FIG. 6, and the bar 50 slides within the raised section 54a of the catch 54.

Referring now to FIG. 7, a locking pin 60 having a catch chain 62 is provided to prevent the inner sash from being raised while the guard is in position. The pin 60 extends through a bore 28 in the top of the inner sash 20 and partway into a bore 29 in the outer sash 22 locking the sashes together. When pin 60 is in the position shown in FIGS. 1 and 7, the inner sash 20 cannot be raised as it is engaged to the outer sash 22 which is at the top of the window frame.

In FIG. 8, a bottom stud 70 is shown mounted within the bottom edge of the guard frame 32 and within a channel 72 in the window sill 18. Stud 70 prevents movement of the window guard either inward or outward at the bottom edge and the stud 70 fits into the circular channel 72 in the sill as the guard is lowered into position.

In FIGS. 9 and 10, the locking means consisting of bars 40 and 50, and catch 54 are shown in greater detail. It can be observed that the bars are formed having opposingly directed end portions and are normally formed from a strong metal such as iron.

The operation of this form of the window safety guard of my invention is substantially as follows. When it is desired to have the window opened but have protection against someone coming in or a child falling out of the window, the window guard of this invention is utilized. The safety guard is slid into the open ends of the two U-channels already attached to the window frame until the safety guard reaches the window sill and the bottom stud 70 falls within the hole provided in the sill. The inner sash is then raised and if the locking means 40 is used, bar 40 is pivoted toward sash 20 so as to engage the sash when it is lowered. If the bar 50 is used then the inner sash must be raised before the safety guard is inserted so that catch 54 will clear the guard. The inner sash is then lowered until the locking bars fit either within the groove in the bottom of the sash or in the catch as shown. Then the top locking pin is inserted through the inner sash until it engages the outer sash thereby preventing movement of the inner sash upwardly. With the inner sash locked against vertical movement, the safety guard cannot be removed from the window because it is held at the sides by the U-channels, at the top by the locking pin and at the bottom by the stud. It should be clear that the locking pin cannot be removed by someone on the outside because the two sashes having glass therein occupy that portion of the window. From the inside, the locking pin is positioned relatively high in the window so that a small child would be unable to grasp the pin and remove it. Even if a child did remove the pin, it is doubtful that he could raise the inner sash and lift the safety guard entirely out of the channels.

The safety guard of my invention may be made in a variety of materials but it is preferred that the guard be relatively light in weight yet consistent with the de-

gree of strength required. A wooden frame could support the metal bars as shown in FIG. 1.

Although this invention has been described with reference to specific forms and embodiments thereof, it will be apparent to those skilled in the art that various changes other than those referred to above may be made in the form of the apparatus, that equivalent elements may be substituted for those illustrated in the drawings, that parts may be reversed, and that certain features of the invention may be used to advantage independently of the use of other features, or within the spirit and scope of the invention as defined in the appended claims.

Having described my invention, I claim:

I claim:

15 A window safety guard for detachable mounting in an open window, said window having a frame and an inner and outer sash mounted for movement within said frame, a channel member mounted against each side of the window frame having an open end, said channel member extending from the bottom of the frame to a position not higher than the middle of the frame, a safety guard comprising a frame and means mounted within said frame for preventing access therethrough, said frame being mounted within said channel members so that the frame can be only removed by sliding out of the open ends of said members, means for locking said frame to the inner sash while said sash is in the raised position, said means comprising at least one generally Z-shaped, short length rigid bar having opposingly directed end portions, one end portion of said bar positioned within holding means in the lower portion of the inner sash and the other end portion of said bar positioned within the upper portion of the safety guard frame and an elongated, substantially uniform diameter stud extending through the inner sash and into the outer sash when said outer sash is in the raised position so that further upward movement of the inner sash to disengage the locking bar is prevented.
